VERTOT D. BEACH, OF BATTLE CREEK, MICHIGAN.

Letters Patent No. 86,631, dated February 9, 1869.

IMPROVED RAILWAY-CURVE.

The Schedule referred to in these Letters Patent and making part of the same.

To all whom it may concern:

Be it known that I, VERTOT D. BEACH, of Battle Creek, in the county of Calhoun, and State of Michigan, have invented a new and improved "Railroad-Curve;" and I do hereby declare that the following is a full and exact description of the same, reference being had to the accompanying drawings, and to the letters of reference marked thereon.

This invention relates to an improved construction of rails for curves upon railroads; and consists in forming the inner rail of the curve of greater breadth than usual, and giving it an oval form upon its upper surface.

The general object of this construction is to permit the wheels of cars to pass around the curves without slipping upon the track, or grinding against the rails, and this largely increases the safety of trains in passing such parts, by diminishing the natural tendency to run off the track.

The special object of this invention is to permit the inner rail to be readily adjusted for curves of different radius.

The details of construction and the manner of operation will be fully described hereinafter.

In the drawings—

Figure 1 is a plan view of my invention;

Figure 2 is a section of road, with wheels of a car represented thereon; and

Figure 3 is an enlarged cross-section of my improved rail.

To enable those skilled in the art to make and use my invention, I will proceed to describe its construction and operation.

A A represent the cross-ties of a railroad-curve, and

B C, the rails of the same, the inner one, C, of which is constructed wider than the outer, and of oval form upon the top.

H represents the outer wheel of a car, and D, the inner, both being of the ordinary tapering construction, and connected by the axle F.

It is well known that railroad-curves are a great source of wear to both the running gear of cars and on the rails composing said curves, by reason of the great strain to which the rails are subjected, by the tendency of the wheels to run off at a tangent, this strain being particularly great on the outer rail.

To obviate this difficulty, I construct my inner much wider than the outer, and give it an oval form on its upper surface, as before mentioned.

The direct result of this construction is to virtually diminish the circumference of the inner wheel, by which means the latter passes over less space in the same time, than the outer wheel.

The result is effected by causing the inner wheel to bear upon the rail, at a point near its outer edge, when its periphery is smaller, while the outer wheel bears upon its rail, at a point near its inner edge, when its periphery is larger. This position of the wheels, while passing a curve, is clearly shown in fig. 2.

For the purpose of adjusting the rail and curves of different radius, I provide the rail with an oval top, as is shown in fig. 3. By this construction I am enabled to make nice adjustments for curves of different radius by elevating the outer edge of the rail more or less, to bring the bearing of the inner wheel nearer or further from the inner edge of the rail, by which means, of course, the wheel may be rendered practically larger or smaller, as may be desired.

I adjust the rail by wedges, as is shown in fig. 2, or sinking its inner edge into the tie.

If the track-master finds that the flanges of the outer wheels grind against the rail, the outer edge of the rail C should be elevated, in order that the inner wheel may tread upon a smaller part of its periphery, and *vice versa* if a contrary result is produced.

The inner rail should be, in practice, constructed of sufficient width, that the wheel cannot bear upon its edges and break it down. The width in other respects is not essential.

Having thus fully described my invention,

What I claim as new, and desire to secure by Letters Patent, is—

The broad rail C, having an oval top, when arranged as described, and when used for curves, in connection with the ordinary tapering car-wheels, as and for the purpose set forth.

VERTOT D. BEACH.
